[57] CLAIM

The ornamental design for a necklace with illuminable pendant, as shown and described.

DESCRIPTION

FIG. 1 is a front elevational view of a necklace with illuminable pendant showing my new design, the continuous cord being broken away for ease of illustration;

FIG. 2 is a left side elevational view thereof;

FIG. 3 is a right side elevational view thereof;

FIG. 4 is a rear elevational view thereof;

FIG. 5 is a bottom plan view thereof; and

FIG. 6 is a top plan view thereof.
